UNITED STATES PATENT OFFICE

2,034,224

PROGRAM DEVICE FOR PLAYER MUSICAL INSTRUMENTS

Willard J. Butler, Scituate, Mass.

Application June 15, 1934, Serial No. 730,773

7 Claims. (Cl. 161—1)

The principal object of the present invention is to provide a program device for musical instruments whereby a plurality of power player musical instruments of different type may be started successively, each at a definite timed interval after the starting of another and stopped, each at the conclusion of the rendition of a record; whereby an electrically operated power player musical instrument may be started successively at timed intervals; and whereby said instruments, or any of them, may be controlled electrically from a distant point.

Various other objects of my invention will be apparent from the detailed description of the particular embodiment thereof selected for more fully disclosing the principles underlying the same.

In the drawing which accompanies and forms a part of this specification,—

Figure 1 is a diagram of apparatus and certain arrangements embodying my invention; and Fig. 2 is a plan view of a detail of construction.

In the particular drawing selected for more fully disclosing the principle of my invention, 10 is a horometric device such as an electric clock of any suitable type having a rotor 11 and a field structure 12 provided with a coil 13. In Figure 1 the horometer is shown in side elevation. Connected in any suitable manner for actuation by the horometer is a switching device herein shown as a mercury switch 14 disposed in the tilting cradle 15, pivotally connected at 16 to a suitable framework, said cradle having two up-standing arms 17, 18 at its respective ends. While various means may be employed for tilting the switch 14 at the proper times, I have shown for the purpose of more clearly disclosing the invention a spring-retracted lever 19 pivoted at 20 and arranged to coact with the arm 17 of the cradle for tilting the mercury switch to circuit-closing position (Fig. 1) when the head 21 of said lever is moved by any suitable appliance actuated by the horometer. The cradle having no retractile means, the switch 14 will remain in circuit-closing position until tilted to circuit-opening position by means hereinafter described, and vice versa. As shown in the drawing, the horometer is connected through a gear train 22 and worm gears 23, 24 with the vertical sleeve 25 to which are secured radially-extending blades arranged in sets herein shown as four in number. The first set consists of a single blade 26 which is of greater vertical height than any of the blades of the other sets and performs the function of ac-

tuating the lever 19 once every hour. The second set consists in the present instance of two blades 27, 28, the blade 27 being of less vertical height than the blade 26. The set consisting of the blades 26 and 27 actuates the lever 19 every half hour. The third set in the present instance consists of four blades 26, 27, 28, 29. The blades 28, 29 are of less vertical height than the blades 26, 27 and the set consisting of the blades 26, 28, 27, 29 actuates said lever 19 every quarter hour. The fourth set of blades comprises the blades already mentioned and four other blades 30, 31, 32 and 33, each being of less vertical height than the blades 28, 29 and with the four blades already mentioned performing the function of actuating the lever 19 on every eighth hour. The sleeve 25 is arranged to rotate about the internally-threaded sleeve 34, restrained from rotational movement and arranged to be moved vertically by the screw 35 which terminates in the knob 36, said knob 36 being disposed on the top of the casing 37 which encloses the horometric control.

The upper and lower ends of the sleeve 25 are provided with flanges which extend over the inner threaded sleeve 34, so that by turning the knob 36 the latter is raised and lowered, thereby raising and lowering the four sets of blades above described and placing any desired set in suitable position for co-action with the head 21 of the lever 19.

As explained in detail in my prior Patent 1,783,375, December 2, 1930, it is desirable to actuate player musical instruments at definite timed intervals so that there will be an appreciable interval after the conclusion of the rendition of a record before the beginning of another; I have ascertained that it is desirable artistically to play such instruments of different type alternately or successively, each at a definite timed interval after the starting of another, with an appreciable time interval after the conclusion of the rendition of a record by another (which is herein called alternate operation) or else to start one instrument at successive definite time intervals and another immediately after the conclusion of the rendition of a record by said instrument (which is herein called paired operation).

Before describing in detail alternate and paired operation I shall explain the circuit arrangements whereby a power player instrument such as a pneumatically operated piano is started at successive definite time intervals, with an appreciable interval between the conclusion of the

rendition of one record and the playing of another.

In the circuit arrangements shown in the drawing which is to be considered as illustrative merely and not restrictive, the main or "on-off" switch 40 and the "piano" and "interval" switches 41, 42 are closed, thereby closing and opening certain circuits and initiating a train of operations as follows: The closing of the double pole switch 41 closes the following circuit: From the contact point 43 to the solenoid 44 and thence to one side of the plug 45 connected to a suitable source such as a house lighting system, then through the switch 40, to the point 46 and thence by the conductor 47 back to the switch 41. The closure of said circuit causes the momentary energization of the solenoid 44 so designed that the plunger is advanced beyond its central position and immediately falls back to such position. The switch 48 is thus momentarily closed by said solenoid core and immediately thereafter opened whereby an impulse of current is sent over the following circuit: From the point 49 to the switch 40, plug 45 and thence by conductor 50 through the lefthand coil of the relay or starting controller 51 the two coils of which are identical and then back by conductor 52 to said switch 48. The energization of said coil of said relay 51 swings the armature 53 to the left and closes the four-blade switch at the points 54, 55, whereupon the following two circuits are closed: (1) From one side of the switch 54 by the conductor 56 to the motor 57 and then by the conductor 50 to one side of the supply line and thence via the switch 40 and conductor 58 to the other side of said switch 54; (2) from the switch 55 by the conductor 59 to the righthand coil of the relay 51, thence by the lead 60 to the supply line 50, the switch 40, point 46, conductor 47, switch 41, contact point 61, switch points 62, closed in the manner hereinafter set forth, points 63, 64 and thence by lead 65 to the switch points 55. The two coils of the relay 51 being identical it will be clear that upon the simultaneous energization thereof the armature 53 will remain in whatever position it occupied at the time of such energization.

The closure of circuit (1) above traced results in the energization of the motor 57 connected by gear train 66 to the rotating cam 67 whereby the switch 62 is closed irrespective of the initial angular position of said cam. The closure of circuit (2) traced above and the resultant energization of the righthand coil of relay 51 open the circuit of said motor at the switch points 54, thereby causing the cam 67 to remain in position to maintain the switch 62 closed, and simultaneously opens the circuit of said righthand winding of the relay 51 at the switch points 55. The closure of the switch 68 effected as aforesaid by the cam 67 closes the circuit of the piano-actuating motor as follows: From the switch points 68 by the line 69 to the piano motor 70 and thence by the conductor 71 and point 72 to the plug 45, switch 40, mercury switch 14 and finally via lead 73 back to the switch 68.

It will be understood of course that the horometer controls not only the intervals between the starting of the piano motor but also the instant of time at which the instrument is started in the first instance. For example, if it is desired to play a given instrument on the quarter hours beginning at 11:00 o'clock a. m., not only is the knob 36 turned to such position that the lever 19 will be actuated on the quarter hours, but also 75 a "future start" apparatus, not shown because

well known in this art, (see for example Patent No. 1,789,057, Jan. 13, 1931) is set to render the horometric control of the switch 14 ineffective until 11:00 o'clock a. m.

At the conclusion of the rendition of each record, a "stop" perforation effects the operation of a pneumatic 73, as well understood in this art, which pneumatic in the present instance briefly closes the switch points 74 and 75, thereby closing the following circuits: (1) From the switch points 74 by conductor 76 to the lefthand coil of the relay 51, via the point 74', and thence by conductors 60 and 59 to the plug 45 and switch 40, conductor 58, point 77 and thence back by conductor 78 to said switch points 74; and (2) from the switch points 75 by conductors 79 and 80 to the interval switch 42, thence by conductor 81 to point 82 and then by conductor 83 to the magnet 84, then back to said switch points 75 by conductor 85, plug 45, switch 40, conductors 58 and 78.

The closing of circuit (1) traced above and the resultant energization of the lefthand winding of the relay 51 effects the closure of the switches 54, 55, as above explained, causing the cam 67 to rotate sufficiently to clear the switches 62, 68 and immediately thereafter the switches 74, 75 are opened by the pneumatic 73'. The armature 53 remaining in its lefthand position and the switches 54, 55 remaining closed, the cam will continue to rotate until it again closes the switches 62, 68 whereupon, as above described, the circuit of the motor 57 will be opened. The closure of circuit (2) above traced and the resultant energization of the magnet 84 effects the tilting of the cradle 15 and the mercury switch 14 carried thereby downwardly or counterclockwise about its pivot 16 through the intermediary of the armature 86 and the pin 87 projecting laterally from the arm 18. Such counterclockwise tilting of said switch opens the circuit of the piano motor 70. The switch 14 will remain in circuit-opening position until the cradle is again tilted in a clockwise direction by the arm 19. At the end of the next quarter hour, in the instance herein assumed, the cycle of operations above set forth is repeated.

In order to start an electrically-operated power player musical instrument, for example, an electrically-operated automatic record-shifting phonograph, the switch 88 is closed and thereupon the circuit shifts and the series of operations above described are effected with the exception that the cam 67 is stopped at the position shown to close the switches 89, 90 and if such instrument is to be started at successive definite timed intervals the switch 91, as well as the switch 88, is closed, with the result above set forth in connection with the description of the pneumatic instrument control operation. Upon the completion of the rendition of a record the switches 92, 93 are briefly closed mechanically by a lug 94 affixed to a suitable portion 95 of the automatic record-shifting device, with the result above set forth in connection with the switches 74, 75.

By means of the switch 96 any other type of power player musical instrument such as a pipe organ may be controlled continuously in the manner above described in connection with the control of the piano by means of the switch 41 alone, or by closing the switches 97 and 96 may be controlled at successive timed intervals, in the manner above described in connection with the control of the piano and the phonograph when the switches 42 and 91 are closed in conjunction with the switches 41 and 88, respectively. At the con- 75

clusion of the rendition of a record by an organ or other instrument controlled by the switch 96, the switches 98, 99 effect the stopping of said instrument in the manner above set forth in connection with the switches 74, 75 and 92, 93 by a pneumatic 100, or other suitable device.

The circuit-changing switches are automatically opened immediately after each shift of the control of the horometer from one instrument to another in order to clear the circuits and restore the same to normal condition.

Pleasing effects may be obtained by arranging matters so that at a given hour a power player musical instrument of one type will start and then stop at the conclusion of the rendition of its first record and an instrument of another type will start at a definite timed interval after the starting of the instrument first mentioned and at an appreciable interval after the conclusion of the rendition of a record by the latter, the first instrument again playing at a definite interval after the starting of the second, and the cycle continuing. This mode of operation I term "alternate". Specifically, if the knob 36 is set on the quarter hour so that the blades 26, 28, 27 and 29 are placed at the height to co-operate with the head 21 of the lever 19, the future starting device set at 1:00 o'clock p. m. and the switches 41, 42, 88 and 91 closed, the piano will render a composition at 1:00 p. m. for, say, four minutes, there will then be an interval of silence for eleven minutes, the phonograph will then begin its rendition at 1:15 and will stop, say, at 1:18, there will then be a period of silence until 1:30, whereupon the piano will again start its next number and play until 1:35, for example, there will be a period of silence until 1:45 whereupon the phonograph will start its next rendition, and so on. If three power player musical instruments such as a piano, a phonograph and an organ are employed, as indicated in Fig. 1, these instruments are started successively, each at a definite timed interval after the starting of another and are stopped by the means above described, each at the conclusion of the rendition of its record, there being an appreciable interval after the conclusion of the rendition of a record by any instrument before the starting of the next.

Another novel and pleasing effect can be obtained by setting the apparatus to start two instruments successively, one immediately after the conclusion of the rendition of a record by the other, and then after an interval of silence repeating the operation. For example, if the piano switch 41, the phonograph switch 88 and the interval switch 91 are closed, the switch 42 remaining open, and the knob 36 set as before, for starting an instrument on the quarter hour, the piano will be started at the time indicated by the future starting device, say at 2:00 o'clock p. m., and will play, say, three minutes, whereupon the phonograph will start immediately after the conclusion of the rendition of the record by the piano and will continue to play for say three minutes. There will then be an interval of silence until 2:15 whereupon the paired operation will be repeated, and so on. The most pleasing way to employ "paired control" is to have both instruments play the same composition, the second rendition of such composition being termed an "echo".

This mode of control may be extended of course to include three or more instruments of different type such as the piano, the phonograph and the organ, as indicated in Fig. 1, in which case

switches 41, 88, 96 and 97 will be closed, if the sequence of play is to be piano, phonograph and organ, although as will readily be understood any other sequence can be used.

This system of switches makes possible the playing of any instrument, either continuously or with intervals between each number, and also makes possible the setting up of the variety of program combinations at will.

Inasmuch as the horometer is arranged to operate on the hour or even divisions thereof, it can be used to advantage in the timing of radio programs.

It will be understood of course that in the form shown in the drawing the worm wheel 24 makes one complete revolution every hour.

Obviously the switches 41, 42, 88, 91, 96, 97 and 43, and the horometric control apparatus may be suitably enclosed in a housing and located at a point remote from the instruments and the rest of the system, or as indicated by the breaks 101, the entire system, suitably housed, may be located at a distant point for the remote control of the instruments.

Having thus described an illustrative embodiment of my invention without limiting myself thereto, what I claim and desire to secure by Letters Patent is:

1. A program device for musical instruments comprising in combination a plurality of power player musical instruments of different type, a horometer, a starting controller, means for initially setting said controller to place one of said instruments under the control of said horometer means controlled by said horometer for starting said instruments successively to render records each at a definite time interval after the starting of another, instrument-actuated means for stopping said instruments, each at the conclusion of a record, and means actuated simultaneously with the last mentioned means for setting said starting controller to place another of said instruments under the control of said horometer.

2. A program device for musical instruments comprising in combination two power player musical instruments of different type, a horometer, a starting controller, means for initially setting said controller to place one of said instruments under the control of said horometer, means controlled by said horometer for starting said instruments alternately to render records, each at a definite time interval after the starting of another, instrument-actuated means for stopping said instruments, each at the conclusion of a record, and means actuated simultaneously with the last mentioned means for setting said starting controller to place another of said instruments under the control of said horometer.

3. A program device for musical instruments comprising in combination a plurality of power player musical instruments of different type, a horometer, a starting controller, means for initially setting said controller to place an instrument of one type under the control of said horometer, means controlled by said horometer for starting said instrument at successive definite time intervals to render records, instrument-actuated means for stopping said instrument at the conclusion of each record and for simultaneously resetting said starting controller to effect the starting of an instrument of another type immediately after the stopping of the instrument first mentioned.

4. A program device for musical instruments comprising in combination a plurality of power

player musical instruments of different type, a horometer, a starting controller, means for initially setting said controller to place one of said instruments under the control of said horometer, means controlled by said horometer for starting said instrument to render a record, instrument-actuated means for stopping said instrument at the conclusion of the rendition of such record and for simultaneously resetting said starting controller to effect the starting of another of said instruments immediately after the stopping of the instrument first mentioned.

5. A program device for musical instruments comprising in combination a plurality of power player musical instruments of different type, a horometer, and means controlled by said horometer for starting said instruments at predetermined times, said means comprising two oppositely disposed electromagnets, an armature 15 mounted for oscillation between said electromagnets, an instrument-actuated limit switch controlling the circuit of one of said electromagnets, a plurality of instrument-selector switches, one for each of said instruments, an electromagnetic 20 device for actuating said instrument-selector switches successively, and means actuated by said armature for controlling said electromagnetic device.

6. A program device for musical instruments comprising in combination a plurality of power player musical instruments and means for start-

ing said instruments successively to render records, each at a definite time interval after the starting of another, said means comprising a plurality of instrument-selector switches, one for each of said musical instruments, two oppositely-disposed electromagnets, an armature mounted for actuation by said electromagnets, a normally-open switch closed by said armature when actuated by one of said electromagnets, normally-open switches disposed for actuation simultaneously with said instrument-selector switches, respectively, a circuit connecting the winding of the other of said electromagnets with said normally-open switches and means for successively actuating said instrument-selector switches.

7. A program device for musical instruments comprising in combination a power player musical instrument, a horometer, a starting controller, means for initially setting said controller to place said musical instrument under the control of said horometer, means controlled by said horometer for starting said instrument at successive definite time intervals to render records, instrument-actuated means for stopping said instrument at the conclusion of the rendition of a record, and means actuated simultaneously with the last mentioned means for setting said starting controller to place said instrument again under the control of said horometer.

30 WILLARD J. BUTLER.
